UNITED STATES PATENT OFFICE.

EDWIN B. STIMPSON, OF BROOKLYN, NEW YORK.

DESIGN FOR A STRAP.

SPECIFICATION forming part of Design No. 18,788, dated December 4, 1888.

Application filed October 30, 1888. Serial No. 289,562. Term of patent 7 years.

To all whom it may concern:

Be it known that I, EDWIN B. STIMPSON, of Brooklyn, in the county of Kings and State of New York, have invented and produced a 5 new and original Design for a Strap, of which the following is a specification.

I will describe my design for straps in detail, and then point out the novel features in a claim.

10 The accompanying drawing illustrates a strap showing my design.

This strap has substantially parallel side edges. Near each of the side edges thereof and extending lengthwise of the strap is de- 15 lineated a zigzag line, *a*. About midway in the width of the strap, and also extending

lengthwise thereof, is delineated a band, *b*. This band is composed of a number of approximately parallel lines, *c*, extending at right angles to the direction of the length of 20 the band.

What I claim as my design is—

The design for a strap having approximately parallel side edges, and a surface ornamentation consisting of zigzag lines *a* and an intermediate band, *b*, composed of substantially parallel lines *c*, substantially as shown and described. 25

EDWIN B. STIMPSON.
